CARPET.

No. 17,501.

Patented July 26, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,501, dated July 26, 1887.

Application filed June 18, 1887. Serial No. 241,805. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The main feature of my design is the figure A, which is repeated upon the face of the carpet upon any suitable ground. The body of

this figure is of a diamond shape, and its ornamentation is geometrical in character. At the top of the figure is a block-work ornamentation shaped like a miter. At the bottom of the figure are three pendent conventional forms harmonizing the ornamentation at the top. At the sides are three small cross figures. The figures A are arranged close together over the face of the design.

What I claim as new, and desire to secure by Letters Patent, is—

The design for carpets, consisting of the design substantially as shown.

HENRY HUNT.
